INVENTOR.

RAYMOND G. MOORE.

BY *John Matteson*.

ATTORNEY.

UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

LATCH.

Application filed February 14, 1924. Serial No. 692,635.

This invention relates to latches, and especially a latch of the type adapted for use with kitchen cabinets or the like, an object being to provide a spring latch of this character which is of extremely simple construction, and which will be efficient and reliable in operation.

It is particularly proposed to provide a latch constructed from two main parts in the form of sheet metal stampings, and including an actuating spring, and which parts may be assembled with facility by a single operation.

A further object is to provide an improved form of latch lever, made from sheet metal, and formed to produce a structure of great strength and having smooth rounded edges.

Other objects are to provide a latch which is compact and relatively flat, neat in appearance, and which will not readily get out of order.

With the above and other objects in view, an embodiment of the invention is shown in the accompanying drawings, and this embodiment will be hereinafter more fully described with reference thereto, and the invention will be finally pointed out in the claims.

30 In the drawings:

Fig. 1 is a front elevation of a latch and keeper, according to the present embodiment of the invention, and shown attached to a door and door frame respectively;

35 Fig. 2 is a front elevation of the latch, and showing in dotted lines one of the operative positions of the lever member;

Fig. 3 is a rear elevation of the latch;

Fig. 4 is a side view thereof;

40 Fig. 5 is a sectional view taken along the line 5—5 of Fig. 2;

Fig. 6 is a plan view of the flat sheet metal blank from which the lever member is formed;

45 Fig. 7 is an end view thereof;

Fig. 8 is a plan view of the lever member after the first forming operation;

Fig. 9 is an edge view thereof;

Fig. 10 is a plan view of the completed

lever member, and after the second forming 50 operation;

Fig. 11 is an edge view thereof; and

Fig. 12 is a side view of the keeper adapted to be employed with the latch.

Similar reference characters indicate corresponding parts throughout the several figures of the drawings.

Referring to the drawings, the latch, according to the present embodiment of the invention, comprises a sheet metal base 10 of vertically elongated shape widened at the center, and having a marginal rim 11 bent rearwardly to contact with the surface of the door or other structure upon which the latch is mounted. Adjacent the upper 60 and lower ends there are provided holes 12 for engagement of the attaching screws 13, and at its central portion and inwardly spaced from the rim 11 a circular boss 14 is pressed up, the upper surface of which is 70 substantially flat, while the circular wall is substantially cylindrical.

The lever member, which is adapted to be pivotally connected to the base, comprises an intermediate circular portion 15 of 75 greater diameter than the boss 14 and provided at its upper and lower edges with a rearwardly bent circumferential rim 16, adapted to surround the cylindrical wall of the boss 14 in annularly spaced relation 80 thereto. An outwardly curved handle 17 extends at one side of the portion 15, and at the other side and in diametric relation to the handle there is provided an extended keeper engaging bar portion 18 inwardly 85 offset with relation to said portion 15. In order to reinforce the handle and bar portion, and to provide a smooth rounded edge, a marginal flange 19 in continuation of the rim 16 is bent under and along the edge 90 of the handle, and similarly, marginal flanges 20, also in continuation of the rim 16, are bent under and along the upper and lower edges of the bar portion.

The base and lever members are assembled 95 by means of a shouldered stud or rivet 21 engaged in a central hole 22 of the lever member and in a central relatively smaller

hole 23 of the base, the same being non-rotatably secured to the base member by upsetting the inner end, as at 24, so that the lever member may rotate freely.

5 A coil spring 25 is disposed within the hollow of the boss 14, one end of which is fixed by hooking, as at 26, in a hole 27 provided in the cylindrical wall of the boss, while the other end is bent outwardly, as at 10 28, through a slot 29 in said cylindrical wall of the boss, and is fixedly inserted in a hole 30 in the circumferential rim 16 of the lever member.

The spring, it will be understood, normally maintains the lever member in its horizontal position, and in which position it engages to keeper 31 secured to the door frame. By depressing the lever handle against the pressure of the spring to the limit permitted 15 20 by the slot 29, the bar portion 18 may be raised, as indicated by dotted lines in Fig. 2, to free it from the keeper and allow the door to be opened. As shown in Fig. 12 the keeper is provided with a beveled forward 25 edge so that upon closing the door the lever member will be automatically rotated to raise the bar portion, and will thereupon drop into its horizontal or latched position under the action of the spring.

30 A feature of the invention is the novel structure of the lever member and the method of forming the same by pressing operations from a single piece of sheet metal. As shown in Figs. 6 and 7 a flat blank 32 is stamped out of sheet metal, being provided with the central rivet engaging hole 22, and having sufficient marginal material to form the rim 16 and the reinforcing flanges 19 and 20. The next step consists 35 40 in pressing the blank in a suitable die to bend the rim 16 at right angles to the circular portion 15, and to bend under the reinforcing flanges 19 and 20 of the handle and bar portion, as shown in Figs. 8 and 9. 45 Thereupon the same is subjected to a second pressing operation to curve the handle and to offset the bar portion, as shown in Figs. 10 and 11. The lever member thus produced is of one piece, its edges are smooth 50 and rounded, and the handle and bar portions are of sufficient strength to withstand the most severe usage.

I have illustrated a preferred and satisfactory embodiment of the invention, but it will be obvious that changes may be made therein, within the spirit and scope thereof, as defined in the appended claims.

Having thus described my invention, what I claim and desire to secure by Letters 60 Patent is:

1. In a latch, a base member having a slot opening, a lever member pivotally mounted on said base member, and a spring disposed within said base member having one end 65 secured to said base member and the other

end extending through said slot opening and secured to said lever member, said spring end adapted by abutment against one end of said slot opening to determine the normal operative position of said lever member and by abutment against the other end to limit the effective movement of said lever member. 70

2. In a latch, a base member having a circular boss including an annular wall provided with a slot opening, a lever member pivotally mounted on said base member, and a spring disposed within said base member having one end secured to said base member and the other end extending laterally through said slot opening and secured to said 80 lever member, said spring end adapted by abutment against one end of said slot opening to determine the normal operative position of said lever member and by abutment against the other end to limit the effective 85 movement of said lever member.

3. In a latch, a base member having a circular boss including an annular wall provided with a slot opening, a lever member pivotally mounted on said base member and having a circumferential rim portion surrounding said boss annularly and having a hole in lateral alignment with said slot opening, and a spring disposed within said boss at its under side having one end secured 90 to said base member and the other end extending laterally through said slot opening and engaged in said hole in the rim of the lever member, said spring end adapted by abutment against one end of said slot opening to determine the normal operative position of said lever member and by abutment against the other end to limit the effective 95 movement of said lever member.

4. In a latch, a base member formed from 105 sheet metal and including a circular boss pressed therefrom and having an annular wall provided with a slot opening, a lever member formed from sheet metal pivotally mounted on said base member and having a downwardly bent circumferential rim portion surrounding said boss annularly and having a hole in lateral alignment with said slot opening, and a spring disposed within said boss at its under side having one 110 end secured to said base member and the other end extending laterally through said slot opening and engaged in said hole in the rim of the lever member, said spring end adapted by abutment against one end of 115 said slot opening to determine the normal operative position of said lever member and by abutment against the other end to limit the effective movement of said lever member.

5. In a latch, a base member having a circular boss including an annular wall provided with an opening, a lever member formed from sheet metal and including a central circular portion pivotally mounted on said base member and having a circum- 120 125 130

ferential rim portion surrounding said boss annularly, a handle portion having a marginal bent under flange in continuation of said rim, and a bar portion having a marginal bent under flange in continuation of said rim, and a spring disposed within said boss at its under side having one end secured

to said base member and the other end extending through said opening and secured to said rim of the lever member.

10

Signed at Bridgeport, county of Fairfield, and State of Connecticut, this 12th day of February, 1924.

RAYMOND G. MOORE.
